UNITED STATES PATENT OFFICE.

RAYMOND L. BARKER, OF CHICAGO, ILLINOIS.

SURFACE-ABRADING DEVICE.

Application filed January 7, 1924. Serial No. 684,697.

To all whom it may concern:

Be it known that I, RAYMOND L. BARKER, a citizen of the United States, and resident of Chicago, in the county of Cook and State of Illinois, have invented a certain new and useful Improvement in Surface-Abrasing Devices, of which the following is a full, clear, concise, and exact description, reference being had to the accompanying drawings, forming a part of this specification.

My invention relates to surface abrasing or sanding devices which are adapted to be moved along the work to be treated, and more especially to that type of abrasing devices which carry individual driving motors. One object of my invention is the provision of supporting rollers so disposed that they tend to carry the device along the work obliquely to the abrasing element whereby a faster and more perfect cutting may be effected.

Among its other objects, my invention contemplates improved means for adjusting the depth of the abrasing cut, for securing the sand paper or other abrasing element to a rotary drum, and for housing the gears between the motor and the abrasing drum.

The accompanying drawings illustrate these and other features of my invention as I prefer to employ it.

Figure 1 being a plan view of the abrasing device;

Figure 2, a vertical longitudinal section thereof taken along the line 2-2 of Figure 1;

Figure 3, a transverse vertical section along the axis of the drum taken on the line 3-3 of Figure 2;

Figure 4, a detail vertical section taken along the line 4-4 of Figure 1, showing the electric switch housed by one of the handles; and

Figure 5, a detail section taken on the line 5-5 of Figure 3, showing the means which clamp the sand paper to the drum.

The abrasing device here shown comprises in general a rotary sanding drum 10 mounted within a housing 11 and driven by an individual electric motor 12, the housing being pivotally mounted by a rod 13 to a carriage 14 adapted to be carried along the work by a pair of rollers 15. Because of their pivotal connection, the housing and the carriage constitute in effect a hinged

frame for the drum. The periphery of the drum 10 is covered by a sheet of sand paper or other abrasing element 16 secured by means which will later be described. A shaft 17 extends through the drum 10, and at each end thereof is provided with ball bearings 18 and 19 for journalling the drum within the housing 11. To one end of the shaft 17 is secured a pinion 20 which is driven through a spacing gear 21 by the driving pinion 22 of the electric motor 12. The armature shaft 23 of the motor is similarly journalled by ball bearings 24 and 25 to the housing 11.

From Figure 3, it will be seen that the housing is divided by a vertical partition 11^a and a horizontal partition 11^b into three compartments, one containing the drum 10, the second, the motor 12, and the third, the gears 20, 21 and 22. By thus enclosing the three above mentioned units in separate compartments, there is no opportunity for oil or grease from the gearing compartment to get to the drum and hence to the work, and similarly, dust carried up by the drum cannot find its way into the motor compartment nor into the gearing compartment. The bottom of the drum compartment is, of course, left open allowing the drum to extend downwardly to the work to be abraded.

The armature shaft 23 preferably carries a fan 26 adapted to draw air through a plurality of suitable holes 27 in the housing for the purpose of cooling the motor, the warm air preferably being discharged through holes in a closure plate 28. Access may be had to the motor compartment by the removal of the closure plate 28. By means of felt washers 29, substantially oil-tight seals are made around the bearings 25 and 18, allowing the gear compartment to be filled with lubricating oil. Access may be had to the several gears by removal of the plate 30 which extends across one end of the housing.

The carriage 14 comprises a pair of lateral rails 31 and transversely extending end rails 32, the end rails being oblique to the lateral rails whereby the carriage is given a trapezoidal contour. The rollers 15 are provided with trunnions 33 for journalling them in the lateral rails of the carriage parallel with the end rails 32. As clearly shown in Figure 1, the rollers 15, while

mutually parallel, lie obliquely to the axis of the drum 10 and likewise to the housing 11.

Since the rollers 15 tend to carry the device along the work in a direction at right angles to their axes, the drum is moved obliquely to its rotary or driven direction whereby the surface of the work is given a somewhat diagonal abrasion. One of the advantages of such a diagonal cutting action is that a large piece of grit on the abrading element will not tend to dig a groove along the surface of the work. A faster cutting action is also made possible because the work can be cut partly across the grain of the work rather than wholly with the grain. While I have shown this feature applied only to a device having the abrading element wrapped about the surface of the drum, it is obvious that the invention could be applied to those devices wherein the abrading element is in the form of an endless belt.

As previously mentioned, the housing 11 is pivotally secured to the frame 14 by a rod 13. The pivot rod 13 is supported at its ends in the lateral rails 31 and passes through lugs 34 extending outwardly from adjacent the base of the housing 11 and adjacent the respective lateral rails of the carriage. At the opposite side of the housing, I provide a bridge 35 extending between the lateral rails and parallel with the housing, the mid portion of the bridge being formed as a boss 36 through which is threaded a vertical adjusting screw 37, the lower end of which screw carries a knurled thumb disc. A knurled lock nut 38 is provided for locking the screw 37 at the desired height relative to the bridge 35. A lug 39 extends outwardly from the adjacent wall of the housing 11, and through a suitable aperture in the lug extends the upper and reduced end 37' of the screw 37. This reduced portion 37' is threaded and provided with a thumb nut 40 for limiting the upward movement of the lug 39. A compression spring 41 is interposed between the lug 39 and the bridge 35 for urging the housing upwardly about its pivot on the rod 13 to lift the drum 10 above the bottom of the rollers 15 and out of engagement with the work.

It is to be observed that the pivotal axis of the housing as it swings upon the rod 13 is parallel with the axis of the drum—or more accurately, with the line of contact between the periphery of the drum and the surface of the work. In this way I overcome any tendency to form ridges or grooves caused by one end of the abrading element digging more deeply into the work than the other end.

In using the abrading device, the operator grasps the handles 42 and 43 secured to the front and rear sides of the housing 11 and pushes downwardly upon the handles

as he reciprocates the device along the work to be abraded. Pressure on the handle 43 will swing the housing 11 around the pivot rod 13 and force the abrading drum 10 into engagement with the work, the depth of the cut made by the abrading drum being limited by the lower edge of the lug 39 which engages the shoulder of the screw 37. The height of this shoulder above the bridge 35, and consequently the depth of the cut made by the abrading drum, may be adjusted by unscrewing the lock nut 38 and turning the screw 37 to the desired height when the screw may again be locked by the nut 38. As soon as the operator removes the pressure from his hands, the spring 41 will lift the housing sufficiently to carry the drum out of engagement with the work so that no grooves will be formed therein when the machine is not being moved. The height to which the spring carries the drum may be varied of course by the thumb nut 40 on the upper end of the screw 38.

I prefer that one of the handles 42 or 43 house the switch mechanism which controls the motor 12, so that the operator may be able to start and stop the machine with the greatest convenience. In Figure 4, I have shown the handle 43 hollowed by a suitable bore, within which is inserted a switch mechanism 44 of a well known type wherein the manually engageable lever 45 is adapted to snap a moving contact member 46 into engagement and out of engagement with a stationary contact member 47.

I shall now describe in detail the means previously referred to for securing the sandpaper 16 or other abrading element to the periphery of the drum 10. The drum is provided with a bore 48 extending longitudinally thereof from end to end and spaced a short distance inwardly from the periphery of the drum. Within the bore 48 is rotatably mounted a pin 49 extending the length of the drum. At a plurality of spaced points the pin 49 is turned down to form eccentric reduced portions 50 which constitute crank arms. Over each of these crank arms 50 is hooked a J-shaped rod 51, the straight end of which is secured in a wedge strip 52, which clamps the ends of the sand paper strip in a slot 53 provided in the periphery of the drum. One end of the pin 49 is slotted as at 49', whereby a screw driver may be used to rotate the rod to swing the eccentric arms 50 outwardly from the center of the drum and release the wedge strip 52 along the ends of the sand paper strip 16 to be withdrawn and replaced by a new strip of sand paper. To relock the sand paper upon the periphery of the drum, the pin 49 is again turned to swing the crank arms 50 inwardly, pulling the wedge strip 52 into the slot 53 to clamp the ends of the sand paper. For locking the pin 49 against

accidental rotation, I employ a screw 54 tapped into the end of the drum for holding a washer 55 which overlaps a portion of the end of the pin 49 to clamp the latter securely against rotation.

As shown by the dotted lines of Figure 1, the slot 53 extends somewhat obliquely along the periphery of the drum 10, so that at all times during the rotation of the drum a portion of the abrading element is in actual contact with the surface of the work. Even though the drum is rotated at high speed, this biased position of the break in the abrading element tends to eliminate vibration which would otherwise be caused by the periodic impact of the posterior edge of the slot.

Having thus described the preferred embodiment of my invention, I claim:

- 20 1. In a portable sander unit, the combination of a carriage, a single abrading drum pivotally supported on said carriage, means for driving said drum, the rotation of said drum tending to confine motion of said carriage along a path at right angles to the axis of said drum, and a pair of rollers on said carriage disposed at an angle to said drum for compelling said unit to travel along a divergent path.
- 30 2. In a portable sander unit, the combination of supporting means, a single power driven sanding element mounted on said supporting means, the motion of said sanding element tending to cause said supporting means to move along a path in a definite angular relation to said sanding element, and a roller on said supporting means for compelling said unit to travel along a different path.
- 40 3. In a portable sander unit, the combination of a carriage, rollers adjacent the front and rear ends thereof, a frame pivotally supported on said carriage, a single abrading drum pivotally supported on said frame, means carried by said unit for driving said drum, handle means for depressing said frame to bring said single abrading drum into engagement with the work intermediate the ends of said carriage, the rotation of said drum tending to direct motion of said carriage along a path at right angles to the axis of said drum, one of said carriage rollers being disposed obliquely to said drum for compelling said unit to travel along a path at right angles to said roller.
- 50 4. In a portable sander unit the combination of a carriage of general trapezoidal form, a roller at the front end of said carriage, a roller at the rear end of said carriage, a frame pivotally supported on said carriage, a single abrading drum pivotally supported on said frame, with its axis oblique to the axis of said rollers, power means carried by said unit for driving said drum, spring means normally holding said frame raised

with said drum out of contact with the surface to be abraded, handle means for depressing said drum into contact with the surface at a point intermediate the ends of said frame, the obliquity of said drum tending to direct motion of said carriage along one path and said end rollers compelling motion of said carriage along another path.

5. A surface abrading device comprising a frame adapted to rest upon and be moved along the surface of the work to be abraded, and a housing adjustably secured thereto, said housing being partitioned into three compartments, the first housing an abrading drum, the second, an electric motor for driving said drum, and the third, gearing between said motor and said drum, whereby oil is prevented from passing from the gearing to said motor or said drum, and dust is prevented from passing to said gearing or said motor, said first compartment having an opening at the bottom thereof through which a portion of said drum extends.

6. A surface abrading device comprising a carriage adapted to rest upon and be moved along the surface of the work being abraded, a housing pivotally mounted on said carriage, which housing encloses and supports an abrading drum, a motor for driving said drum, and a power transmitting mechanism between said motor and said drum, said housing being partitioned into three compartments which contain respectively the said motor, drum, and mechanism, and a handle on said housing whereby the operator may move said device along the work and whereby the operator may push said drum into engagement with the work.

7. In a portable sander unit, the combination of a carriage, rollers at the front and rear ends of said carriage, a housing pivotally supported on said carriage, an abrading drum pivotally supported in the lower portion of said housing with its axis oblique to the axis of said rollers, an electric motor enclosed in the upper portion of said housing, a partition forming a gear compartment in one end of said housing, gearing in said compartment connecting said electric motor with said abrading drum, a spring normally holding said housing in a raised position with said abrading drum out of contact with the work surface, handles projecting from the opposite sides of said housing for rolling said carriage and for depressing said housing, and screw threaded abutment means between said housing and said carriage for limiting the depression of said housing.

8. In a portable sander unit, the combination of a carriage, rollers at the front and rear ends of said carriage, a housing disposed intermediate said rollers, pivot lugs projecting from said housing, pivots con-

necting said lugs to said carriage, an abrad-
ing drum pivotally supported in the lower
portion of said housing, an electric motor
pivotally supported in the upper portion of
5 said housing, a partition separating the
drum compartment from the motor comp-
artment, a vertical partition adjacent one
end of said housing forming a gear com-
partment, a gear on a motor shaft in said
10 last named compartment, a gear on the
drum shaft in said last named compartment,
an idler gear in said compartment connect-
ing said gears, a support carried by said car-
riage, a lug on said housing, a spring con-
15 fined between said support and said lug for
normally holding said housing in raised po-
sition, an adjustable screw threaded abut-
ment means between said support and said
lug and a handle for depressing said hous-
20 ing, said abrading roller contacting with
the work at a point intermediate the ends of
said carriage.

9. In a portable unit of the class de-
scribed, the combination of a carriage hav-
25 ing front and rear rollers, a housing pivot-

ally supported on said carriage, a first par-
tition in said housing forming a drum com-
partment and a motor compartment, an
abrading drum in said drum compartment,
an electric motor in said motor compart-
ment, a second partition in said housing
30 forming a gear compartment separate from
said first named compartments, the shafts of
said motor and of said drum extending
through said second partition into said gear
compartment, bearings carried by said sec-
ond partition for said shaft, gears on each
35 of said shafts, means in said gear compart-
ment operatively connecting said gears,
packing means associated with said bear-
ings for excluding the lubricant in said gear
compartment from said motor and drum
40 compartments, and air impelling means for
circulating air through said motor compart-
ment.

In witness whereof, I hereunto subscribe
my name this 31st day of December, 1923.

RAYMOND L. BARKER.

Witness:

J. DAVID DICKINSON.
